UNITED STATES PATENT OFFICE.

ROBERTO RODRIGUEZ, OF DETROIT, MICHIGAN.

AUTOMOBILE SIGNAL DEVICE.

Application filed October 8, 1924. Serial No. 742,290.

This invention relates generally to automobile accessories, the invention relating more particularly to a novel form of illuminated license plate and stop signal device, which may be used during day or night.

The invention has for an object the provision of a simple and inexpensive device in which the numbers and the name of the state are cut in the license plate, behind which a lamp is positioned to reveal said numbers at night.

For further comprehension of the invention, and of the objects and advantages thereof, reference will be had to the following description and accompanying drawing, and to the appended claims in which the various novel features of the invention are more particularly set forth.

Fig. 1 of the drawing is a face view of my improved device.

Fig. 2 is a transverse sectional view taken on the line 2—2 of Fig. 1.

Fig. 3 is a horizontal sectional view taken on the line 3—3 of Fig. 2.

Fig. 4 is an enlarged fragmentary transverse sectional view taken on the line 4—4 of Fig. 1.

Referring now to the drawing, the reference numeral 10 indicates an elongated casing that is of the general form of the frustum of a cone as seen in end view, this casing having its narrower side closed by an integral wall member 10 while its opposed side, which forms the face of the casing, is arranged to receive the license plate. The license plate is carried by a rectangular frame element 12 that fits over the face of the casing, the latter presenting adjacent its face the parallel wall elements 10 over which the frame fits snugly. Within this frame is fitted the license plate 13 that has the numbers, or other information, cut therein as in forming stencils, the openings cut in the plate for this purpose being indicated generally at 14. This plate fits against an inturned bead 15 on the front edge of the frame 12. The plate 13 is backed by a glass plate 17 that closes the face of the casing 10 and is preferably colored red. Within the outer casing 10 is fitted a reflector 18 of suitable curvature that has an outturned flange 19 at its edge that engages between the glass plate 17 and the edge of the wall 10 of the casing 10. A lamp 20 is mounted in the casing.

To lock the parts in position I provide the

novel locking means shown, that facilitates removal when desired. As here shown a series of hollow bosses 21 are provided in the casing 10, and fixed to each boss is a cylinder 42 having extending therethrough a rod 22 that has pivotally attached to its inner end as at 23 a hooked latch 24 that projects through a slot 25 in the boss 21 to engage in a notch 26 in the frame 12. The notch in the frame is preferably formed by striking out the metal of the latter as indicated at 27, this struck out part forming a cam that acts to throw the hook 24' of the latch within the confines of the casing when the latch is released. The body of the latch is formed with a tapering end portion 24' that projects through a like aperture in the inner end of cylinder 42. Threaded on the rod 22 is a nut 29 which is tightened upon the outer end of the cylinder to lock the parts in place. Formed within the cylinder is a recess 30 in which is a coiled expansion spring 31 that surrounds the rod and bears on a collar 32 on the latter and acts to urge the latch to released position.

It will be obvious that when the nut 29 is screwed outwardly the spring 31 will urge the latch inward and as the latch moves inward the member 27 will act to throw the hook 24' away from engagement with the frame 12 and so release the latter. When the nut is again screwed inward the engagement of the side of the latch with the inclined side of the passage in the boss causes the hook 24' to be thrown outward to reengage with the frame to lock the parts in place.

Upon the top of the frame element 12 I preferably mount a bracket 35 that has attached thereto a casing 36 in which is a lamp 37 that illuminates a stop signal 38 on the face of the said casing. To mount the whole device on an automobile a pair of rigid straps 40 are attached to the back of the casing and have inclined lower ends to which a plate 41 is attached.

Having thus described my invention what I claim as new and desire to protect by Letters Patent of the United States is as follows:

1. In a device of the class described, a casing element provided with an open face, a closure element for said face, said casing element being provided with integral bosses with rigidly attached cylinders, a rod slideable in each of said cylinders, a hooked latch

pivoted to each of said rods, to engage said closure element, a nut threaded on each of said rods, and abutting the rear ends of said cylinders, to allow movement for said rods, 6 an expansion spring in each cylinder, and bearing against said rods, to normally press the rods forward, and said hooked latches being provided with an oblique side abutting against a portion of said cylinders, to engage 10 said latch upon longitudinal movement, to impart transverse motion thereto, from and to locking positions.

2. In a device of the class described, a casing element provided with an open face, 15 a closure element for said face, formed with notches, said casing element being provided with integral bosses with rigidly attached cylinders, a rod slidable in each of said cylinders, a hooked latch pivoted to each of said rods, to engage the notches of said closure element to lock the same to the casing, a nut threaded on each of said rods, and abutting the rear ends of said cylinders, to allow movement for said rods, an expansion 20 spring in each cylinder and bearing against said rods, to normally press the rods forward, and said hooked latches being provided with an oblique side abutting against 25

a portion of said cylinders forming cam elements, to engage said latch upon longitudinal movement, to impart transverse motion thereto, from and to locking positions. 30

3. In a device of the class described, a casing element provided with an open face, a closure element for said face, formed with notches, said casing element being provided with integral bosses with rigidly attached cylinders aligned with the notches of said closure element, a rod slidable in each of said cylinders, a hooked latch pivoted to 35 each of said rods, to engage the notches of said closure element to lock the same to the casing, a nut threaded on each of said rods, and abutting the rear ends of said cylinders, to allow movement for said rods, an expansion spring in each cylinder, and bearing against said rods, to normally press rods forward, and said hooked latches being provided with an oblique side abutting against a portion of said cylinders forming cam 40 elements, to engage said latch upon longitudinal movement, to impart transverse motion thereto, from and to locking positions. 45

In testimony whereof I have affixed my signature.

ROBERTO RODRIGUEZ.
